UNITED STATES PATENT OFFICE.

ROBERT E. LANGSTON, OF FORT WAYNE, INDIANA, ASSIGNOR TO WAYNE COMPANY,
OF FORT WAYNE, INDIANA, A CORPORATION OF INDIANA.

APPARATUS FOR PURIFYING USED MINERAL LUBRICATING OIL.

Application filed September 27, 1921. Serial No. 503,533.

Mineral lubricating oils that have been used in crank cases of internal combustion engines or other mechanisms where gasoline, kerosene or other volatile liquids have been 5 come mixed therewith, become dirty and unfit for further use, because they contain free carbon, the heavy ends of gasoline, kerosene or the like, used as a motor fuel, water and acid, as well as dirt. Such dirty oils have 10 lost much of their viscosity.

Dirty oils from the crank cases of airplane engines or other internal combustion engines, where an extremely high grade of liquid fuel and lubricants are used, and the engine is necessarily of a very high degree of 15 mechanical perfection, must have scarcely any of the heavy ends of gasoline, less water, and less acid than the lubricating oil from engines of inferior construction.

20 All such oils soon become unfit for further use as a lubricant, because airplane engines must always be maintained at as nearly maximum efficiency as possible, and it is a well known fact that they are then either thrown 25 away, or in some instances used for road oiling.

The lower the grade of gasoline, the more frequently the oil in the crank case will have to be changed in a given engine. The best 30 practice at this time is to drain out the dirty oil and replace it with fresh oil in the crank cases of automobile engines, about once every two hundred miles of travel on trucks and about every five hundred miles of travel on 35 pleasure cars.

This invention relates to a method of and a means for restoring to its original efficiency such used mineral lubricating oil, rendering it fit for re-use as a lubricant.

Restoration to former efficiency involves two changes in the dirty oil being treated; reclaiming, that is, the removal of gasoline, kerosene or other volatile constituents, and clarifying, that is, the removal of carbon, dirt, or the like.

Such apparatus in order to be practical must be capable of operation by persons of ordinary mechanical ingenuity, be free from danger of ignition of volatile fluids driven off, be free from danger of explosion and the

operation must be cheap enough to make such restoration to efficiency practical.

This invention consists in the combination of such elements as will by their united action have these advantages, and produce the results above set forth, and these will be 60 hereinafter particularly pointed out.

Some of the apparatus heretofore used have been inefficient in that the body of oil to be treated was heated by steam and therefore no temperature could be secured or 65 maintained above 212° Fahrenheit.

The apparatus herein described and claimed is designed for use particularly on oils that are not too dirty to be clarified after the volatile constituents have been 70 driven off; a method and means for restoring to their original efficiency very dirty lubricating oils are the subject of a separate application to wit:—Serial No. 503,534 filed Sept. 27, 1921. 75

In the particular embodiment of my invention selected for illustration,

Figure 1, is an elevation of the completed gas heated apparatus, with the internal mechanism shown in dotted lines, and 80

Fig. 2, is a top plan view of the same apparatus with the hood and hood support removed.

Referring now to the drawings:

A, is a vertical cylindrical tank surrounded on its bottom and sides by an oil jacket B, and the whole mechanism is sustained within and supported by a casing C. 85

After the hood D, has been swung to one side, a suitable quantity of dirty oil to be treated is poured into the tank A, as indicated by the oil level shown in Fig. 1.

Within the casing C, and beneath the oil jacket B, is a gas burner E. A heating space 95 c is left between the jacket B and the casing C.

The space between the tank A, and the jacket B is substantially filled with something capable of maintaining a relatively high temperature without vaporizing, as a heavy, high-temperature oil, heat being applied to the body of oil being treated from the jacket oil, as rapidly as possible, until the oil being treated in the tank is brought 100

to that temperature above the boiling point of water, found most suitable for the treatment of the particular oil being restored, in most cases preferably to about 400° Fahrenheit. ⁵ *c* is a heating space.

Gas is fed to the burner E through the pipe *e*.

A thermostat F may be used to fix in advance and maintain the maximum ¹⁰ temperature desired to be obtained in the jacket oil.

In order to coagulate the carbon and other fine dirt in the oil and thus facilitate precipitation, any suitable solution of carbonate ¹⁵ of soda is put into the oil being treated before it reaches a temperature of 212° Fahrenheit, and stirred in.

The coagulant may be added after the volatile constituents of the dirty oil have ²⁰ been driven off, the steam and heat shut off, as hereinafter described, and the oil being treated cooled to below 212° Fahrenheit. In fact this is the treatment I prefer; and also when so used the coagulant should ²⁵ be thoroughly stirred into and mixed with the body of oil being treated.

Immersed in the jacket oil are one or more metal tubes *g*, preferably of copper, to which water is fed through pipe G from ³⁰ any suitable source of supply, and its flow is regulated by the needle valves *g*¹, and fed slow enough to cause said tubes *g*, to act as a flash boiler. To make such an apparatus effective it is desirable that water ³⁵ should drip through said valves *g*¹. When the water supply is taken from a pressure system, a pressure reducing valve *g*², is used in the line. These coils *g* pass from the jacket oil space into the space within the ⁴⁰ tank A where they terminate in a ring *g*³, in the bottom of the tank A. This ring *g*³, is provided with a relatively large number of small holes from which the heated steam, generated by heat from the burner E, ⁴⁵ escapes into the body of the oil under treatment, and thereby agitating the oil.

In order to keep the oil from backing up into this steam coil a sufficient distance to cause trouble, the steam coil is passed from ⁵⁰ the oil jacketed space into tank A over the top of the tank edge.

After the superheated steam has performed the function of agitating the mass of oil under treatment, it will pass out ⁵⁵ through the opening at the top of the tank A and through the vent opening V in the top of the hood D as steam and at the same time the water, gasoline ends, and other volatile constituents of the contents of the ⁶⁰ tank will be carried off as vapors in the same manner. This process is continued a sufficient length of time to drive off all volatile extraneous matter.

The valves *g*¹ are then closed. The heat ⁶⁵ is shut off by cutting off the supply of gas

to the burner E, and the contents of the tank allowed to cool slowly. Water is then fed in slowly through the pipe H, valve *h*, and cock *h*¹, to the bottom of tank A from any suitable source of supply. That the ⁷⁰ water may not agitate the contents of tank A by carrying air in with it, a standpipe or vent H¹ is provided.

As the water at the bottom forces the body of the oil to rise in tank A, the purified ⁷⁵ oil is carried off through an enlarged inlet I¹, of an overflow pipe I to any suitable storage space. When all the clarified oil has been drawn off the valve *h* is closed and the rest of the contents of the tank may be ⁸⁰ drained to the sewer by opening cocks *h*¹ and *h*².

There is a sampling valve J for drawing off a small quantity of the contents of the tank whenever it is desired during any part ⁸⁵ of the treatment, to test the extent to which the operation has proceeded.

A thermometer K connects with the interior of the tank A so that the temperature of the liquid under treatment may be determined at all times.

Obviously many changes may be made in the apparatus herein shown without departing from the spirit of my invention, as, for instance, a closed steam jacket with the steam under pressure, or a jacket of electrical heating elements; or electrical heating elements may be substituted for the burner, or the gas burner may be omitted and one or more electrical heating elements placed ⁹⁵ in the high temperature oil in the jacket; or the jacket may be filled with asbestos or other non-conductor and the electrical heating elements put in the tank in the body of oil being treated, or any other means of ¹⁰⁵ procuring and maintaining in the body of oil being treated the desired relatively high and relatively uniform temperature, may be substituted for the jacket filled with oil of high flash temperature heated by the gas ¹¹⁰ burner.

I claim as my invention and desire to secure by Letters Patent of the United States:

1. An apparatus for purifying lubricating oil contaminated with volatile fluids and other foreign matter; consisting of a tank adapted to hold said contaminated oil while under treatment, a heating jacket for said tank, means for heating the contents of said jacket to a temperature substantially above 212° Fahrenheit, coils of metal tubing within said jacket and extending from said jacket into said tank and opening thereinto, and means for feeding water into said coils ¹¹⁵ for generating steam.

2. An apparatus for purifying lubricating oil contaminated with volatile fluids and other foreign matter; consisting of a tank adapted to hold said contaminated oil while

under treatment, a heating jacket for said tank, means for heating the contents of said jacket to a temperature substantially above 212° Fahrenheit, coils of metal tubing within said jacket and extending from said jacket into said tank from above the level of oil being treated therein and opening thereinto, means for feeding water into said coils for generating steam, means for feeding water into said tank near the bottom thereof, and means for withdrawing the oil from an upper portion of the tank as the body of oil rises in the tank. ¹⁰

In testimony whereof I have hereunto set my hand.

ROBERT E. LANGSTON.
